UNITED STATES PATENT OFFICE

THOMAS PETER EUSTEGE, OF WELLINGTON, NEW ZEALAND

WINDOW STAY

Application filed August 19, 1929, Serial No. 386,880, and in New Zealand September 11, 1928.

This invention relates to casement stays for windows and the like of the kind in which the stay bar is pivoted in a link pivoted to a bracket fixed to the sash and passing 5 through a bracket attached to the window frame, the end of the stay bar adapted, when the bar is turned at right angles thereto, to retain the sash in its closed position.

According to the present invention, the 10 bracket fixed to the window frame has projecting lugs in which is pivoted a vertical member on pins, passing through such member and the lugs so that such vertical member may rotate therein. The stay bar passes 15 through the member, being adapted to slide freely therethrough, while the link pivoted to the bracket on the sash is also adapted to pass through the member. A pin traverses the member near the lower end and notches 20 in the bottom edge of the stay are adapted to engage over this pin. When the sash is closed the stay is adapted to assume a vertical position so that the bottom edge of the stay bar bears against the edge of the member, 25 thereby retaining the sash closed. As the sash opens, the bar slides through the member, which rotates in order to remain in alignment with the bar.

Associated with the end of the stay bar and 30 the pivoted member may be means whereby a lock or catching action is produced for retaining the sash closed.

The invention will now be described with 35 the aid of the accompanying drawings where- in:

Figure 1, is a side elevation of the stay on a window showing it in its closed and locked position.

Figure 2, is a front elevation of the stay. 40 Figure 3, is a view of the end of the stay bar.

Figure 4, is a section through the link.

Figure 5, is a sectional plan taken along 45 line A—A, Figure 1.

Figure 6, shows an alternative form of the locking device shown in Figure 5.

Figure 7, is a side elevation of the upper 50 part of the stay showing an alternative form of catch or lock.

Figure 8, is a front view of the alternative form.

Figure 9, is a sectional plan along line B—B, Figure 7.

Referring to the drawings, the bracket 1 fixed to the window frame 2 has projecting lugs 3 in which is pivoted a vertical member 4 on pins 5 fixed in the lugs 3 and passing through the member so that it may rotate thereon. The stay bar 6 passes freely through this member, while the link 7, to which is pivoted the bar 6 on its pin 8, is pivoted on a pin 9 in a bracket 10 fixed to the sash 11.

A pin 12 traverses the member 4 near the lower end and notches 14 in the bottom edge of the stay are adapted to engage over this pin to retain the sash in different open positions.

When the sash is closed, as shown in Figures 1 and 2, the stay bar assumes a vertical position so that the bottom edge of the bar bears against the lower edge of the member, as shown in Figure 1, thereby assisting in retaining the sash closed. The link 7 is formed with two projecting tongues 15 and 16 parallel with the link and just above it, but yieldable to open and close. These tongues pass through the pivoted member 4 and, when the stay bar is rotated to a vertical position, as shown in Figure 1, the upper projecting end 17 of the bar will enter between the tongues and expand them against the inner sides of the member. The tongues 15 and 16 have outwardly curved or bent portions 18 which, when they are expanded by the end 17, will engage against the edges of the member shown in dotted lines in Figure 5. In this figure, however, the ends of the tongues are continued in portions 19 which enable them to enter the member and be slightly compressed during the passage therethrough, and spring upwards so as just to engage the outer edges of such member, as shown in full lines in Figure 5, and upon the bar 6 being rotated to its vertical position, the end 17 will pass up between the tongues and further force out the tongues against the inner sides of the members (shown in dotted lines), drawing up the sash and locking it in this position.

This forms a lock to prevent the 100

window being opened from the outside. The end 17 is shaped so as to readily enter between the tongues and may be of the shape indicated in Figures 2 and 3, that is the top front edge being narrowed as indicated at 20.

In Figures 7, 8 and 9, an alternative form of locking is shown. In this case, the sides of the member are formed with a narrowed part by bending the sides inwards, as shown at 21, one side of the member being cut as at 22 so that this side of the member will form a spring to permit the end 17 of the stay bar to pass through. The end of the stay bar 17, on being rotated, to a vertical position, will enter the narrower portion through which it passes, and the sides returning, the edges of the narrowed portions 21 will form a stop for the end 17 of the stay bar, as shown in Figure 9. This will retain the window closed against normal pressure. Upon the bar 6 being raised, the end 17 will be forced through the narrower portion, thus enabling the window sash to be opened as above described. Lips 23 on the narrowed portions ensure the end 17 being guided into the narrower portion of the member.

The sides of the link 7 may be slightly closed at their lower edges, as shown at 24 in Figure 4, so that when the end 17 passes between the sides of the link upon the stay 6 being raised to a horizontal position, such end 17 will tend to hold down the stay and retain the bar in a position on the pin 12.

What I claim is:—

1. In a casement stay of the kind referred to, a bracket fixed to the window frame, a member pivoted in the bracket, a stay bar passing through the pivoted member at right angles to the axis of rotation of the member and adapted to engage at different positions in said member, a link for operably connecting the bar to a window sash so as to leave an end projecting beyond the link when in its final closed position, pressure members between the projecting end of said stay bar passes, said pressure members being forced apart by the passage of the projecting end which when the stay bar reaches its final closed position the projecting end is tensioned past the said pivoted member and thereby is normally prevented from passing through said pivoted member and upon the initial opening movement of the stay the said projecting end will be pressed past the pressure members and the stay bar free to pass through the said pivoted member.

2. In a stay as claimed in claim 1, wherein the pressure members between which the projecting end of the stay bar passes are formed of two opposing flat spring pieces adapted to be forced apart by the passage of the projecting end which when the said stay bar reaches its final closed position lies partly engaging the said members, ready to force

them apart when stay bar is being moved to open the sash.

3. In a stay as claimed in claim 1, wherein the projecting end of the stay bar is shaped so as to easily engage the pressure members and force them apart when passing between such pressure members.

4. In a stay as claimed in claim 1, wherein the pressure members consist of yieldable tongues forming part of the link and pass between the sides of the pivoted member so as to be expanded against the sides of said pivoted member by the stay bar and outwardly extending terminal portions on the pressure members to engage behind the said pivoted member to hold the stay bar in closed position.

5. In the stay as claimed in claim 1, wherein lips are provided on the edges of the pressure member so as to act as guides for the end of said stay bar as the latter is being moved into engagement therewith.

In testimony whereof, I have signed my name to this specification.

THOMAS PETER EUSTEDE.
